(57) **CLAIM**

The ornamental design for a medical diagnostic device, as shown and described.

DESCRIPTION

FIG. 1 is a top, front, left-side perspective view of a medical diagnostic device showing our new design;

FIG. 2 is bottom, front, left-side perspective view thereof;

FIG. 3 a top plan view thereof;

FIG. 4 is a left side elevation view thereof, the right side elevation view being identical thereto;

FIG. 5 is a bottom plan view thereof;

FIG. 6 is a front elevation view thereof;

FIG. 7 is a rear elevation view thereof; and,

FIG. 8 is a top, front, left-side perspective view thereof showing an alternative configuration of the device.

The broken lines in the drawing views are included to illustrate portions of the medical diagnostic device and form no part of the claimed design.
